(57) **CLAIM**

I claim the ornamental design for a data accessing device, as shown and described.

DESCRIPTION

FIG. 1 is a left top perspective view of a first embodiment of a data accessing device showing the claimed design;

FIG. 2 is left bottom perspective view thereof;

FIG. 3 is a front elevational view of thereof;

FIG. 4 is a rear elevational view of thereof;

FIG. 5 is a left side elevational view of thereof;

FIG. 6 is a right side elevational view of thereof;

FIG. 7 is a top plan view of thereof; and,

FIG. 8 is a bottom plan view of thereof.

The broken lines show portions of the data accessing device that form no part of the claimed design.
